UNITED STATES PATENT OFFICE

SAMUEL TAIT, OF PHILADELPHIA, PENNSYLVANIA, ASSIGNOR TO THE VOGUE SILK HOSIERY CO., OF PHILADELPHIA, PENNSYLVANIA, A CORPORATION OF PENNSYLVANIA

DESIGN FOR AN UNDERGARMENT

Application filed June 18, 1931. Serial No. 40,263. Term of patent 14 years.

To all whom it may concern:

Be it known that I, SAMUEL TAIT, a citizen of the United States, residing at Philadelphia, in the county of Philadelphia and State of Pennsylvania, have invented a new, original, and ornamental Design for an Undergarment, of which the following is a specification, reference being had to the accompanying drawing, forming part thereof.

Fig. 1 is a fragmentary rear elevational view of the undergarment, showing my new design;

Fig. 2 is a side elevational view of the undergarment, showing my new design;

Fig. 3 is a plan view of the undergarment, showing my new design; and

Fig. 4 is a fragmentary front elevational view of Fig. 1.

I claim:

The ornamental design for an undergarment, as shown.

SAMUEL TAIT.
